Primary Examiner — Cynthia Ramirez

CLAIM

The ornamental design for a leaf catcher bag, as shown and described.

DESCRIPTION

FIG. 1 is a perspective view of a leaf catcher bag showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof; and,

FIG. 9 is a perspective view of the leaf catcher bag with the bottom tied.

The broken lines depict portions of the leaf catcher bag that form no part of the claimed design.

1 Claim, 9 Drawing Sheets
